Primary Examiner — Deanna L Pratt

(57) **CLAIM**

The ornamental design for a set of pieces for kids couch, as shown and described.

DESCRIPTION

FIG. 1 is a top perspective view of the first piece of a set of pieces for kids couch, showing my new design;

FIG. 2 is a bottom perspective view thereof;

FIG. 3 is a front elevational view thereof, the rear elevational view is identical;

FIG. 4 is a left side view thereof, the right side view is identical;

FIG. 5 is a top plan view thereof, the bottom plan view is identical;

FIG. 6 is a front, left, top perspective view of the second piece of a set of pieces for kids couch, showing my new design;

FIG. 7 is a rear, right, bottom perspective view thereof;

FIG. 8 is a front elevational view thereof;

FIG. 9 is a rear elevational view thereof;

FIG. 10 is a left side view thereof, the right side view being a mirror image of FIG. 10;

FIG. 11 is a top plan view thereof;

FIG. 12 is a bottom plan view thereof;

FIG. 13 is a top perspective view of the third piece of a set of pieces for kids couch, showing my new design;

FIG. 14 is a bottom perspective view thereof;

FIG. 15 is a front elevational view thereof, the rear elevational view is identical;

FIG. 16 is a left side view thereof, the right side view is identical;

FIG. 17 is a top plan view thereof;

FIG. 18 is a bottom plan view thereof;

FIG. 19 is top perspective view of the fourth piece of a set of pieces for kids couch, showing my new design;

FIG. 20 is a bottom perspective view thereof;

FIG. 21 is a front elevational view thereof, the rear elevational view is identical;

FIG. 22 is a left side view thereof, the right side view is identical;

FIG. 23 is a top plan view thereof;

FIG. 24 is a bottom plan view thereof;

FIG. 25 is a top perspective view of the fifth piece of a set of pieces for kids couch, showing my new design;

FIG. 26 is a bottom perspective view thereof;

FIG. 27 is a front elevational view thereof, the rear elevational view is identical;

FIG. 28 is a left side view thereof, the right side view is identical;

(Continued)

FIG. 29 is a top plan view thereof, the bottom plan view is identical;

FIG. 30 is a front perspective view of each piece in the first combined state;

FIG. 31 is a front perspective view of each piece in the second combined state;

FIG. 32 is a front perspective view of each piece in the third combined state;

FIG. 33 is a front perspective view of each piece in the fourth combined state;

FIG. 34 is a front perspective view of each piece in the fifth combined state;

FIG. 35 is a front perspective view of each piece in the sixth combined state;

FIG. 36 is a front perspective view of each piece in the seventh combined state;

FIG. 37 is a front perspective view of each piece in the eighth combined state;

FIG. 38 is a front perspective view of each piece in the ninth combined state;

FIG. 39 is a front perspective view of each piece in the tenth combined state;

FIG. 40 is a front perspective view of each piece in the eleventh combined state;

FIG. 41 is a front perspective view of each piece in the twelfth combined state; and,

FIG. 42 is a front perspective view of each piece in the thirteenth combined state.
